UNITED STATES PATENT OFFICE.

WILLIAM H. TONKS, OF PASADENA, CALIFORNIA, ASSIGNOR OF ONE-HALF TO MARK STEWARD MORSE, OF OAKLAND, CALIFORNIA.

TIMEPIECE.

1,137,245.

Specification of Letters Patent. Patented Apr. 27, 1915.

Application filed June 12, 1912. Serial No. 703,235.

To all whom it may concern:

Be it known that I, WILLIAM H. TONKS, a citizen of the United States, residing at Pasadena, in the county of Los Angeles and State of California, have invented certain new and useful Improvements in Timepieces, of which the following is a specification.

This invention relates to watches, and the principal object of the same is to provide an attachment for a watch by means of which it may be readily ascertained whether or not the watch needs winding. This is accomplished by mounting a disk beneath the face of the watch and forming an opening in the dial so that the disk may be seen through the opening. Certain marks are made upon the disk so that when the disk is in a certain position it is indicated that the watch needs winding. It is, of course, obvious that this disk must be in connection with the axle of the main spring so that as the main spring unwinds, the disk will be rotated.

25 This invention is illustrated in the accompanying drawings, wherein:

Figure 1 is a view in front elevation of a watch having this attachment connected thereto. Fig. 2 is a view similar to Fig. 1 with the dial and hands removed. Fig. 3 is a section along the line 3—3 in Fig. 1. Fig. 4 is an enlarged sectional view through a portion of the watch case.

Referring to the accompanying drawings, it will be seen that this invention comprises the frame which has the inner ring 10 having a groove 11 formed therein in which is seated the plate 12, the edges of the ring 10 being connected by the plate 13, and the dial 14. A band 15 is mounted upon the ring 10, and is provided with the threaded side flanges 16 and 17, these flanges being threaded. The rear cover 18 is threaded upon the flange 17, and the ring 19 which carries the crystal 20 is screwed upon the flange 16. The works of the watch are mounted in the casing between the plates 12 and 13, the drum 21 for the main spring being alone shown. The axle 22 for the main spring drum passes through the plate 12, and has a gear wheel 23 secured to its outer

end. This gear wheel meshes with a larger gear plate 24 which is mounted upon a pivot pin carried by the plate 12, and which is the device which indicates when the watch needs winding. A spot 25 is formed upon the disk 24, and the disk 24 is so mounted with respect to the gear 23 that when the main spring is wound tight the spot 25 will be exhibited through the opening 26 formed in the dial 14. The gear wheel is made of sufficient size in proportion to the gear plate 24 that after the watch has been wound and run for twenty-four hours, the elongated mark 27 will appear at the opening 26, it, of course, being obvious that the gear wheel must turn in the direction indicated by the arrow shown in Fig. 2. When this mark 27 appears it indicates that the watch needs winding, and, since it is intended to have this indicated for a considerable length of time, it is intended that when the watch runs down the mark 27 will not be passed. It will thus be seen that there has been provided a device which will to a great extent eliminate any danger of the watch running down from uncertainty as to whether or not it has been wound and will also prevent any necessity for the watch to be wound a number of times each day in order to be sure that it has been wound.

As is illustrated in Fig. 4, the dial 14 engages the ring 10 and is held in firm engagement therewith by means of a transversely extending binding member A passing through the dial 14 and also through the plate 13. The sleeves B are placed upon the binding member A upon either side of the plate 12, and in this manner firmly hold the plate 12 in spaced relation relative to the dial 14 and plate 13. This structure is illustrated clearly in Fig. 4.

Having thus described my invention, what is claimed is:

In a watch, a frame comprising a ring, upper and lower plates carried by said ring, an intermediate plate positioned within said ring and spaced from said upper and lower plates, a collar carried by said ring and provided with upper and lower off-set externally threaded flanges, a crystal carrying ring provided with an overhanging inter-

nally threaded portion fitting over the upper threaded portion of said first mentioned ring, and a back plate provided with an overhanging internally threaded portion fitting over the lower threaded portion of said first mentioned ring for firmly holding said frame in an assembled position.

Copies of this patent may be obtained for five cents each, by addressing the "Commissioner of Patents, Washington, D. C."

In testimony whereof I affix my signature in presence of two witnesses.

WILLIAM H. TONKS.
